(57) **CLAIM**

The ornamental design for a display panel of a programmed computer system with a graphical user interface, as shown and described.

DESCRIPTION

FIG. 1 is a first view of a first embodiment of a display panel of a programmed computer system with a graphical user interface;

FIG. 2 is a second view thereof;

FIG. 3 is a third view thereof;

FIG. 4 is a fourth view thereof;

FIG. 5 is a first view of a second embodiment of a display panel of a programmed computer system with a graphical user interface;

FIG. 6 is a second view thereof; and,

FIG. 7 is a third view thereof.

The broken lines in the drawings are included for the purpose of illustrating environmental structure and form no part of the claimed design.

The appearance of the transitional image sequentially transitions between the images shown in FIG. 1-4 and FIG. 5-7. The process or period in which one image transitions to another image forms no part of the claimed design.
